METAL SPOOL

Knute G. Anderson, Rockford, Ill., assignor to
 J. L. Clark Manufacturing Co., Rockford, Ill.,
 a corporation of Illinois

Application March 12, 1937, Serial No. 130,453

3 Claims. (Cl. 242—123)

The invention relates to sheet metal spools or reels such as are used for adhesive tape containers, for example.

Spools of this character are ordinarily provided with a tubular core or body member and separate heads or end members, the parts being shipped in knockdown form and the heads secured to the core after the tape or other material has been applied. In applying adhesive tape or plaster to such spools the procedure may be to form a long roll of the plaster on a suitable mandrel, cut the roll transversely into smaller rolls of predetermined width, slide the core into the severed small roll, and then secure the heads in place, or alternatively to place a series of cores on the mandrel before the large roll of plaster is formed and then proceed as described. In either case, it is important that the lengths of the cores should conform exactly to the selected width of the small rolls of tape.

One object of the present invention is to provide an improved form of sheet metal spool in which the core is fashioned in such manner as to afford a structure to which the heads may be readily attached but in which the over-all length is determined with nicety and exactitude.

Another object of the invention is to provide a sheet metal spool having a core member provided with strengthening and securing projections adjacent its ends which are of such character as not to interfere with the formation of a smooth longitudinal seam extending the full length of the core.

Another object of the invention is to provide a novel form of sheet metal spool or reel which is strong and rugged in construction and which is economical to manufacture.

Further objects and advantages of the invention will become apparent as the following description proceeds and the features of novelty which characterize the invention are pointed out with particularity in the claims annexed to and forming a part of this specification.

For a better understanding of the invention reference may be had to the accompanying drawings in which

Figure 1 is a perspective view of a sheet metal spool or reel embodying the invention.

Fig. 2 is a transverse sectional view along the line 2—2 of the spool shown in Fig. 1.

Fig. 3 is a detail perspective view of one of the separable heads included in the spool shown in Fig. 1.

Fig. 4 is a detail perspective view of the core included in the spool shown in Fig. 1.

Fig. 5 is a transverse sectional view along the line 5—5 in Fig. 2.

For purposes of illustration, the invention has been exemplified as embodied in a sheet metal spool particularly adapted for use as a container for adhesive tape or plaster although spools embodying the invention are adapted for a wide variety of other uses. The spool illustrated comprises in general a tubular body 10 having heads 11 secured on opposite ends thereof by an improved construction hereinafter described in greater detail.

The core 10 is preferably formed from a generally rectangular flat sheet of metal rolled or otherwise bent into tubular form. The adjacent edges of the sheet are secured together in the form of an interlocking double seam 12 (Fig. 4) which extends the full length of the core. This elongated seam insures a strong rigid structure and the absence of internal raw edges prevents injury to a user who places his finger within the core in unreeing the tape from the spool.

Each head 11 is formed from a portion of sheet metal centrally apertured so as to form a flat ring or disk, the outer peripheral edges being curled as indicated at 13 (Fig. 2) for finishing and strengthening purposes. The heads may be suitably lithographed or otherwise decorated for purposes of identifying the manufacturer or the like, this operation being performed before the heads are assembled on the ends of the core. Upon reference to Fig. 3 it will be seen that the heads 11 are provided with inwardly extending annular shoulders 14 surrounding axially extending flanges or ring-shaped projections 15 adapted to be inserted into the adjacent ends of the core. The shoulder 14 forms a convenient bearing surface for the end of the core.

Near each end the core 10 is shaped to cooperate with the flanges 15 on the heads 11 in order to secure the heads firmly in position on the ends of the core. In accordance with the present invention, a discontinuous strengthening and locking rib formed by a series of spaced inwardly extending projections is formed on the core 10 adjacent each end. In the particular construction shown, these projections are shown as indentations 16. The spaced relation of the indentations and their small over-all dimensions make it possible to form the same by striking them out of the metal of the core without causing any flow of metal at its marginal edges and consequently, without altering the over-all length of the core. The length of the core may thus be accurately determined by the dimensions of 16

the strip of metal from which it is formed and the subsequent die-forming operations do not alter this dimension. As a result, cores fashioned in this manner may be readily and accurately dimensioned to accommodate convolutions of adhesive tape or the like of predetermined width. In addition, the spaced apart relation of the indentations or projection 16 permits a full length seam 12 to be formed from flat metal as distinguished from the case in which a continuous annular rib or shoulder is formed on the core. If an annular rib were used, the longitudinal seam in the core would have to be stopped short of the shoulder, thus lessening the strength of the core and leaving raw edges of metal exposed at the ends of the seam which might injure the user. In the novel construction herein contemplated, the metal edges at the ends of the core seam are covered by the heads 11.

20 In assembling the spool described above, the core 10 is first fashioned in the form shown in Fig. 4. It may then be inserted in a preformed roll of tape or the like of corresponding width. Sheet metal heads of the form shown in Fig. 3 are then positioned on the ends of the core with the marginal edges of the core abutting against the shoulders 14 and with the flanges 15 extending within the body of the core. The inserted annular flanges 15 are then bent into interlocking relation with the indentations 16 in the form best shown in Fig. 2. It will thus be seen that the resulting structure is strong and rigid and has a core of accurately dimensioned width.

Although a particular embodiment of the invention has been shown and described in some detail for purposes of illustration, there is no intention to thereby limit the invention to this particular form but, on the other hand, the appended claims are intended to cover all modifications within the spirit and scope of the invention.

40 I claim as my invention:

1. A sheet metal spool adapted to receive convolutions of tape or the like of predetermined width comprising, a tubular sheet metal core of predetermined longitudinal length corresponding to the width of the tape or the like, a series of inwardly extending relatively small spaced projections struck out from said core adjacent one end thereof, the spaced relation and dimensions 45 of said projections permitting their formation

without alteration in the length of said core, and a disk-shaped head formed from a separate portion of sheet metal having a part arranged to abut against the end of said core without covering any portion of the exterior surface thereof and having an axially projecting annular portion bent within said core and over said inwardly extending projections in interengaging relation therewith and in the form of a smooth uninterrupted annular bead overlying said projections 10 and covering the same to hold the head firmly in position.

2. A sheet metal spool comprising, a tubular core fashioned from a generally rectangular portion of sheet metal bent into cylindrical form, a discontinuous strengthening and locking rib formed by a series of spaced inwardly extending indentations in said core adjacent one end thereof, the edges of said portion of sheet metal being secured together, in interlocking relation intermediate adjacent indentations whereby a smooth flat seam is provided extending the full length of said core, and a disk-shaped head formed from a separate portion of sheet metal and having an axially projecting smooth annular portion 25 extending within one end of said core and secured in interlocking relation with said indentations and covering the inner ends thereof while leaving the outer surface of said core entirely free and unobstructed.

3. A sheet metal spool adapted to receive convolutions of tape or the like of predetermined width comprising, in combination, a tubular sheet metal core of predetermined length corresponding to the width of the tape or the like, a series 35 of radially inwardly extending spaced indentations formed in said core adjacent one end thereof, and a disk shaped head formed from a separate portion of sheet metal and having a centrally located aperture therein registering with one end 40 of said tubular core, said aperture being bordered by a smooth integral flange on said head extending axially inward within said core with the inner marginal edge thereof bent about the inner sides of said indentations in interlocking relation therewith, whereby said flange not only holds said head in position on said core but also forms a smooth and uninterrupted cover strip for said indentations.

45 KNUTE G. ANDERSON.
